UNITED STATES PATENT OFFICE.

DAVID WALTER HOSTETLER, OF THOMPSONTOWN, PENNSYLVANIA.

RAILWAY CROSS-TIE.

1,102,663.

Specification of Letters Patent.

Patented July 7, 1914.

Application filed March 9, 1914. Serial No. 823,520.

To all whom it may concern:

Be it known that I, DAVID WALTER HOSTETLER, a citizen of the United States, residing at Thompsontown, in the county of Juniata and State of Pennsylvania, have invented certain new and useful Improvements in Railway Cross-Ties, of which the following is a specification, reference being had to the accompanying drawings.

This invention relates to new and useful improvements in railway cross ties and more particularly to a metal cross tie which is provided with means whereby a slight yieldable movement will be conveyed to the track rails which are laid thereon, the tie itself consisting of two detachable parts which can be readily placed in position when it is desired to fix the tie in place upon the road bed.

A further object of the present invention is the provision of a railway cross tie of the above character which will possess advantages in points of efficiency and durability, is inexpensive to manufacture and, at the same time, is simple in construction and operation.

With the above and other objects in view, the invention consists in the novel features of construction, combination and arrangement of parts as will be hereinafter referred to and more particularly pointed out in the specification and claims.

In the accompanying drawing forming a part of this application, Figure 1 is a top plan view of a railway tie constructed in accordance with my invention. Fig. 2 is a side elevation, parts being broken away and illustrated in cross section; and Fig. 3 is a transverse sectional view.

Referring more particularly to the drawing, 1 indicates the body or base of the tie, said base being preferably U-shaped in cross section to form a central channel 2. Removably arranged within this channel is a downwardly projecting rib 3, which is formed upon the under face of the top plate 4 and is securely held within the channel 2, against any longitudinal movement by means of the end plates 5, said end plates being formed integral with the base of the tie and extending upwardly to engage the ends of the tongue 3 and prevent any longitudinal movement of the same.

The base 1 is provided within the channel 2, with the spaced recesses 6, in which the lower ends of the coil springs 7 are arranged,

said coil springs being disposed within the channel 2 and having their upper ends arranged within suitable recesses 8 formed in the downwardly projecting tongue 3. From 60 this, it will be seen that the lower ends of the coil springs bear upon the bottom of the base 1, while the upper ends thereof will yieldably support the top plate 4. In the preferred embodiment of my invention, as 65 illustrated in the accompanying drawing, three coil springs are disposed at each end of the tie, one being arranged directly beneath the track rail and one upon each side thereof, so that the weight upon these coil 70 springs will be evenly distributed.

The top plate 4 is provided with the transverse grooves 9 which are adapted to receive the track rails and formed upon each side of the grooves 9, are the spike receiving openings 10, whereby the track rails may be readily secured in position by the use of the well known form of railway spikes or any other desired fastening means. The base 1 is provided at its central point with a 80 recess 11, said recess being preferably disposed within the channel 2 and mounted therein is a stop pin 12, the upper end of which is removably disposed within a recess 13 formed in the web 3, said stop pin assisting 85 the plates 5 in preventing any longitudinal movement of the top plate 4 of the web 3.

From the above description taken in connection with the accompanying drawing, it 90 will be readily apparent that I have provided a simple and durable sectional tie, whereby one of the sections includes a base member having yielding means mounted therein to support the track rail. In placing 95 the two sections together, the base member 1 is first arranged in position upon the road bed, the coil springs 7 are then placed in position within the recesses 6 and the stop pin 12 is inserted within the recess 100 11. The web member 3 is then passed downwardly between the walls of the channel 2, so that the coil springs 7 and the stop pin 12 will engage within the respective recesses. Thus it will be noted that after the track 105 rails have been placed in position upon the top plate 4, they may be readily secured in place by any suitable fastening means which are engaged within the openings 10. It will be noted that after the tie has been placed 110 in position, the track rails will be yieldably mounted and it is to be understood that the

coil springs 7 are to be sufficiently heavy so as to support the various weights which will pass over the track rails and thus prevent the longitudinal edges of the top plate 5 from being pressed down upon the upper edges of the body member too quickly, as this in time would wear upon the longitudinal edges of the top plate 4, so that they would become almost useless. It will also 10 be apparent that I have provided a simple and durable railway cross tie which is extremely simple in construction and can be manufactured at a comparatively low cost. 15 While I have shown and described the preferred form of my invention, it will be obvious that various changes in the details of construction and in the proportions may be resorted to for successfully carrying my invention into practice, without sacrificing 20 any of the novel features or departing from the scope of the appended claims.

Having thus described this invention, what I claim is:—

1. A device of the class described including a U-shaped body member having closed ends, a plurality of spaced recesses formed in the bottom of said body, coil springs mounted within the recesses at the ends of the body, a retaining pin within the central recess, a top plate, a downwardly projecting web formed upon the upper end thereof

having a plurality of recesses adapted to receive the upper ends of the coil springs and the stop pin as and for the purpose set forth.

2. A device of the class described including a U-shaped body member having closed ends, said body member having spaced recesses formed at each end thereof and further provided with a central recess, coil springs arranged within the recesses at the ends of the body, and a removable stop pin arranged within the central recess; a top plate, a downwardly projecting tongue member formed upon the inner face thereof, 45 having spaced recesses formed in its ends, and a central recess, the upper ends of said coil springs being arranged within the recesses at the ends of the tongue and so disposed that the central coil spring is arranged directly beneath the track rail, and the upper end of the stop pin being disposed within the central recess in the tongue to prevent longitudinal movement of the top plate.

In testimony whereof I hereunto affix my signature in the presence of two witnesses.

DAVID WALTER HOSTETLER.
